(57) **CLAIM**

The ornamental design for an incubator, as shown and described.

DESCRIPTION

FIG. 1 is a top, front and right side perspective view of an incubator showing my new design; the incubator having two separate sections, the transparent top cover and the bottom base;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view showing the bottom base section;

FIG. 10 is a perspective view showing the bottom base section with two troughs in a disassemble state;

FIG. 11 is an enlarged view of portion 11 in FIG. 1;

FIG. 12 is an enlarged view of portion 12 in FIG. 2;

FIG. 13 is an enlarged view of portion 13 in FIG. 2;

FIG. 14 is an enlarged view of portion 14 in FIG. 7;

FIG. 15 is an enlarged view of portion 15 in FIG. 9; and,

FIG. 16 is an enlarged view of portion 16 in FIG. 10.

The evenly dashed broken lines illustrate features of the incubator that form no part of the claimed design. The unevenly dashed broken lines define the boundary of enlarged views and form no part of the claimed design.
